UNITED STATES PATENT OFFICE.

LEO J. GRUBMAN, OF NEW YORK, N. Y., ASSIGNOR TO GRUBMAN ENGINEERING & MANUFACTURING COMPANY, OF NEW YORK, N. Y., A CORPORATION OF NEW YORK.

ACOUSTIC MEANS FOR SOUND-PRODUCING DEVICES.

Original application filed November 18, 1922, Serial No. 601,725. Divided and this application filed January 23, 1924. Serial No. 687,917.

To all whom it may concern:

Be it known that I, LEO J. GRUBMAN, a citizen of the United States, and a resident of the city, county, and State of New York, have invented certain new and useful Improvements in Acoustic Means for Sound-Producing Devices, of which the following is a specification.

This invention relates to an acoustic means for sound producing devices and has for its primary object to provide a simple and effective means for improving the acoustic properties of such devices which have become known in the art as "voices" and are intended for use in connection with dolls or other toys for the purpose of simulating a characteristic cry.

The subject matter of the present application is a division of my prior application for patent filed November 18, 1922, Serial No. 601,725. As disclosed in said prior application, I provide a casing or housing for the sound producing and emitting mechanism and within one end thereof there is arranged a wall or partition which provides a sound receiving and modifying chamber of fixed or constant dimensions within which the emitted sounds are received in the movement of the air expelling member, said sounds being deflected and directed by said chamber wall through the perforated head on one end of the casing. Thus in the emission of sounds simulating the pronunciation of the infant cry ma-ma, since the sound impinges upon only one directing wall or surface throughout the movement of the sound emission controlling member, the same audible effect in the sounding of each syllable will be produced when the sounds are finally emitted through the perforated end wall of the casing.

In my present application I disclose several alternative embodiments of the sound deflecting and directing means illustrated and described in my prior patent application. The essential feature of each of these constructions resides in the provision of the sound producing and emitting means which consists of two parts, one slideable relative to the other and a sound deflecting and directing wall bearing a definite constant relation to the point of sound emis-

sion and providing a sound receiving and modifying chamber of fixed dimensions. Thus during the emission of the sound, the sound waves impinge only upon said chamber wall by which they are deflected and directed from said chamber.

It is a further general object of my invention to provide an acoustic means for sound producing devices of the above character which is simple in its construction, reliable and effective for the purpose in view and will not materially add to the production cost of such devices.

With the above and other objects in view, the invention consists in the combination, construction and relative arrangement of the several parts as will be hereinafter more fully described, illustrated in the accompanying drawing and subsequently incorporated in the subjoined claims.

In the drawing wherein I have illustrated several simple and satisfactory embodiments of the invention and in which similar reference characters designate corresponding parts throughout the several views:

Figure 1 is a vertical sectional view of a sound producing device provided with one embodiment of my present improvement and corresponding to that shown in my prior patent application above identified;

Figure 2 is a similar view of the device with the present improvement omitted therefrom to illustrate the difference in the deflection of the emitted sounds during the movement of the slideable air expelling member;

Figure 3 is a view similar to Figure 1, illustrating a slightly different construction; and

Figures 4 and 5 are sectional views showing other alternative embodiments of the invention.

Referring first to Figure 1 of the drawing which illustrates a construction corresponding to that disclosed in my prior application, the several parts of the sound producing and emission controlling means as well as the sound modifying or acoustic means which constitutes the particular subject matter of the present application are enclosed within a shell or casing 5 of suitable dimensions and may be constructed of heavy cardboard or other suitable mate-

rial. Preferably, though not necessarily, this shell or casing is of cylindrical form and one end thereof is provided with an air tight closure in the form of a metal 5 plate or cap 6 which may be applied to the end of the casing wall and permanently fixed thereon in any approved manner. This end plate or cap also securely clamps and fixes one end of the tubular flexible 10 bellows wall 7 in connection with the wall of the casing 5, the other end of said flexible bellows wall having its edge secured upon the marginal edge of a movable head or air expelling member 8 by any suitable 15 means whereby an air tight seal between said flexible wall and the movable head is effected.

Upon the other end of the casing or shell 5 the sheet metal end plate or cap 9 is secured, the marginal portion 10 of said end plate being offset. Between the end edge of the casing wall and this annular offset portion 10 of the end plate, the annular flange 11 formed upon the edge of the concavo-convex 25 wall 12 is positioned. This wall extends within the shell or casing 5, the concave side thereof being opposed to the plate 9 and is centrally provided with an opening 13 the purpose of which will presently appear.

30 Each of the end plates 6 and 9 is centrally formed with a seat or depression 14 to receive one end of a tubular post 15. This post adjacent one of its ends is provided with the orifice 16 affording communication 35 between the bellows chamber and the interior of said post. Adjacent to this orifice the sound producing reed 17 is suitably mounted within said post.

The member 8 is centrally formed with a 40 tubular extension or sleeve 18 having slideable engagement with the post 15, and said sleeve in one side thereof is provided with a circumferentially extending slot or opening 19. The wall of the tubular post 15 adjacent to the outer concave surface of the sound deflecting wall 12 is also provided with a circumferentially extending sound 45 emission slot 20 therein with which the slot or opening 19 in the sleeve 18 is adapted to register. In addition to the slot 20 the wall 50 of the tubular post 15 adjacent to the end plate 9 of the casing is provided with a small orifice 21 through which nasal sounds are emitted.

55 It will be seen from the above that the space between the concave side of the wall 12 and the end plate 9 provides a sound receiving and directing chamber into which the sounds are emitted during the sliding 60 movement of the air expelling member 8. The tubular extension or sleeve 18 of this member moves freely through the central opening 13 in said wall. The end plate 9 on the casing is provided with a plurality of 65 final sound emission openings 22 through

which the sound waves are directed by the wall 12 externally of the shell or casing 5. I have referred to the sound deflecting wall 12 as being of concavo-convex shape or form, but it will be manifest that this particular 70 form is not absolutely essential, the only material consideration being that such wall shall bear a constant definite relation to the sound emission slot or orifice 20 between said point of sound emission and the movable head 8 so that the sounds are received within a chamber of fixed dimensions and will always impinge upon a single-deflecting and directing surface. This may be better 75 understood from reference to Figure 2 of the drawings wherein I have shown such a sound producing device with the wall 12 omitted. Thus at one point in the movement of the head 8 as shown in full lines, the sound waves issuing from the emission 80 slot 20 will first impinge upon the end face of the bellows head 8 by which they are deflected against the wall of the casing 5 which finally directs the sounds outwardly through the openings in the end plate of the casing. 85 Thus sound waves following this course will produce a certain audible effect upon the ear. When, however, the bellows head 8 is nearing the end of its air expelling movement and approaches the position seen in 90 dotted lines in Figure 2, the sound waves will follow a different course and as indicated by the dotted lines, will first strike the inner surface of the casing wall at one side thereof and then be deflected against the 95 surface of the bellows head and then deflected upwardly and against the opposite side of the casing wall and then finally outwardly through the openings in the end plate of the casing. Obviously, therefore, 100 the sounds finally emitted in the latter portion of the travel of the movable bellows head will have a different pitch or audible effect upon the ear from those which were emitted during the initial part of the travel 105 of the bellows head. Accordingly, the two syllables of the word ma-ma will not be sounded alike but the first syllable will be 110 ma, while the second syllable will sound more like me or mi.

115 The objectionable feature of such a device as shown in Figure 2, I have succeeded in entirely overcoming by interposing the sound directing and deflecting wall between the emission slot or opening 20 and the movable bellows head so that the sounds will always be received within a chamber of fixed dimensions and will impinge always upon the one directing wall 12 so that the final emission of the interrupted sounds through 120 the perforated end plate of the casing whereby the two syllables of the word ma-ma are simulated, will be the same.

125 It will be understood that in the initial movement of the head 8 from the dotted 130

line position shown in Fig. 1 to expel air from the bellows chamber through the reed 17, the small orifice 21 is first uncovered by the sleeve 18 so that the sound will issue through this orifice in small volume in simulation of the letter m. In the continued gravity movement of the bellows head, the opening 19 in said sleeve registers with the opening 20, the emitted sounds 10 simulating the letter a and thus sounding the syllable ma. The sound waves passing laterally through the registering slots 18 and 20 will following substantially the course indicated by the dotted line in Figure 15 1, and impinge at spaced points on the concave surface of the wall 12 and be finally directed by said wall outwardly through the openings 22 in the end plate of the casing. As the head 8 continues its movement, 20 the end portion of the sleeve moves over and closes the slot 20 so that the letter m is again sounded by the emission of sound through the orifice 22 until the end of said sleeve passes below the slot 20 when there 25 will occur a final prolonged sounding of the letter a until the bellows head 8 comes to a position of rest, thus completing the sounding of the second syllable ma. It will, of course, be understood that such 30 control and emission of the sounds simulating the two syllables takes place in rapid succession. However, it will be apparent that by reason of the provision of the sound deflecting and directing wall 12, these two 35 word syllables will be phonetically identical, there being no audible difference in the sound of the final letter of the second syllable from the corresponding letter of the first word syllable.

40 In the construction shown in Figure 1 of the drawings, owing to the fixed position of the wall 12 with respect to the casing and the sound emission control means, the casing 5 must be of somewhat greater length 45 than in certain cases might be found desirable. Therefore, in Figure 3 of the drawing, I have shown a slightly modified form in which the sound deflecting and directing wall 12' is not fixedly clamped and secured 50 at its upper edge against the casing wall 5. In this instance, the end plate 9' has a relatively wide marginal flange 10' suitably clinched at its edge upon the casing wall. The edge of the concavo-convex wall 55 12 has a narrow outwardly turned flange 11' thereon which is adapted to abut against the end edge of the casing wall and limit the inward movement of the wall 12'. It will be seen that in this case the inner part 60 of the wall 12' rests upon the movable bellows head 8 in the initial movement of the latter, during which movement said head 8 and the wall 12' move together during the sounding of the letter m and until the 65 flange 11' contacts against the end edge of the casing wall. The bellows head 8 then continues its independent gravity movement and immediately after the wall 12' reaches the position seen in dotted lines, the opening 19 comes into registration with the slot 20, thus emitting sound through the latter slot simulating the letter a, as above explained. Therefore, it will be seen that in this instance also, during the emission of sound waves through the slot 20, the wall 12' bears a constant definite relation to the point of sound emission and is interposed between said point and the moving bellows head so that the sound waves may not impinge upon said bellows head and be deflected thereby in the manner indicated in Figure 2 of the drawing.

70 In Figure 4 of the drawing I have illustrated another type of such sound producing devices wherein a fixed axially extending post 15' of solid construction is positioned between the casing heads and the movable bellows head 8' is not provided with the tubular extension or sleeve. In this case the solid post 15' is formed with spaced circumferentially extending channels or sound passages 20' and the sound producing reed 17' is mounted in an opening provided 75 in the bellows head 8.

80 In this modified construction, the sound deflecting and directing wall 12' is carried by the movable bellows head and for the purpose of facilitating the assemblage of the parts, I provide this wall of cylindrical form having at one of its ends a lateral flange extension 23 which is adapted to be engaged over the end edge of the tubular bellows wall to frictionally clamp and hold the same upon the marginal edge of the head 8'. At the juncture of the flange 23 with the cylindrical sound directing wall, said flange is provided with an angular offset portion 24 affording a recess or a 85 100 rabbet to receive a disc 25 having a central opening 26 coaxially related with the opening in the head 8' which receives the fixed post 15'. This opening 26 is the point of sound emission and instead of being stationary as in the constructions above described, is movable with the bellows head. The cylindrical wall 12' is of such length 105 that the sound waves emitted through the opening 26 will impinge against the inner surface of said wall and will not pass through the open end thereof and first 110 strike the side wall of the casing. As indicated by the broken lines, any sound waves which do pass directly from the opening 26 through the open end of the cylindrical wall 25, would be emitted through the openings in the end plate of the casing without first impinging against the side wall thereof. Thus in this case likewise, 115 it will be seen that I provide a sound receiving chamber of fixed dimensions and a 120 125 130

sound deflecting and directing wall which bears a constant relation to the point of sound emission during the gravity movement of the bellows head.

- 5 In Figure 5 of the drawing I have illustrated a slightly different form of the sound deflecting and directing member shown in Figure 4 and in which this wall, carried by the movable bellows head, is of dished concavo-convex form as indicated at 12^b and has a central reversely curved or inwardly pressed portion 12^c provided with the central opening 12^d through which the sounds are emitted. Thus the portion 12^c of said 10 wall forms a sound receiving chamber open at its outer side, and the sound waves emitted through the opening 12^d as it successfully registers with the sound passages or channels in the fixed post 15' will impinge 15 against this inwardly curved section 12^c of the wall and be directed thereby through the openings in the end plate of the casing.

From the foregoing description considered in connection with the accompanying drawing, the construction and manner of operation of the several illustrated embodiments of the device will be fully understood. It will be appreciated that by arranging the sound deflecting and directing wall as shown 20 in Figure 3, or as in Figures 4 and 5, the entire mechanism may be completely enclosed and housed within a casing or shell of minimum length. Various other constructions 25 may also suggest themselves from the several forms herein illustrated whereby this desired result can be obtained. It will be understood therefore that the present invention is not to be limited to any particular form or shape of the sound deflecting and 30 directing wall or the mounting and arrangement thereof within the shell or casing, and I believe that I am the first in the art to provide a device of this character wherein both the sound producing and emission control 35 means and the acoustic means, whereby the enunciation of the word syllables is perfected, are entirely enclosed and housed within a shell or casing. Accordingly, it is to be understood that though I have herein disclosed 40 several practical and desirable embodiments 45 of my present improvements, the subject matter thereof might also be exemplified in numerous other alternative constructions and I accordingly reserve the privilege of 50 resorting to all such legitimate changes in 55 the form, proportion and relative arrangement of the several parts as may be fairly embodied within the spirit and scope of the invention as claimed.

60 I claim:

1. In a sound producing device, a casing open at one end to permit the emission of sound therethrough, a sound producing and controlling means enclosed within said casing including a part having a sound emission 65

opening and a sounding reed, an air compression chamber within the casing having a stationary head and a head movable by gravity between the open end of said casing and the stationary head of the air compression 70 chamber, and operating to force air through said sounding reed, and means for deflecting and directing the emitted sound through the open end of said casing.

2. In a sound producing device, a casing open at one end to permit the emission of sound therethrough, a sound producing and controlling means within said casing including a sound box having a sound emission opening in its wall, a sounding reed, an air compression chamber within said casing having a stationary head and a head movable between the open end of the casing and said stationary head for expelling air under pressure through said reed and the sound box, 80 and a sound deflecting and directing wall within said casing bearing a constant definite relation to said opening during the emission of sound therethrough.

3. In combination with a casing having 90 sound emission openings in one end wall thereof and sound producing and controlling means enclosed within said casing for interruptedly emitting sound within the casing, said means including a movable part; a 95 sound deflecting and directing wall also enclosed within said casing extending between the point of sound emission and the apertured end wall of the casing and interposed between said end wall and the movable part 100 of said sound producing means to provide a sound emission receiving chamber of fixed dimensions, said wall directing the emitted sounds through the apertures in the casing wall to the external atmosphere. 105

4. In combination with sound producing and emitting means including a bellows having a movable head and a part having a sound emission opening and with which a part of said bellows head is slidably engaged to control the emission of sound from said opening; a sound deflecting and directing wall bearing a constant definite relation to said opening in the emission of sound therethrough in the sliding movement of 110 said bellows head and forming a sound receiving and directing chamber of fixed dimensions, said chamber being open at one of its ends through which the sounds are finally deflected by said wall. 115

5. In combination with sound producing and emitting means including a bellows having a tubular flexible wall and a movable head closing one end of said tubular wall, a fixed part with which a part of said bellows head coacts to control the emission of sound; a sound deflecting and directing wall having a part concentrically disposed with relation to said fixed part and providing a sound receiving and directing chamber of 120 125 130

fixed dimensions, said wall also having an annular marginal portion adapted for frictional clamping engagement over the end edge of the tubular bellows wall to secure 5 the same to said movable head, said first named part of said wall deflecting and directing the emitted sounds from one end of said chamber.

6. In combination with a casing having 10 openings in an end wall thereof, sound producing and emitting means enclosed within said casing and including coating fixed and relatively movable parts for interruptedly controlling the emission of sound into said 15 casing; means carried by said movable part for deflecting and directing the emitted sounds and consisting of a wall concentrically related to said fixed part and providing a chamber of fixed dimensions having 20 an open end opposed to the openings in the end wall of the casing and through which the emitted sounds are finally directed by said chamber wall.

7. In combination with a casing having 25 openings in an end wall thereof and sound producing and controlling means enclosed within said casing including a bellows having a flexible tubular wall and a movable head closing one end of the bellows chamber; sound deflecting and directing means consisting of a wall disposed in concentric relation to the bellows head on one side thereof and providing an open ended chamber to receive the emitted sounds, said wall being provided with means at one of its ends for 30 frictional clamping engagement upon the end edge of the tubular bellows wall to secure the latter to said movable head and the wall of said chamber deflecting and directing the emitted sounds from the open 35 end of said chamber through the openings in the end wall of the casing.

In testimony that I claim the foregoing as my invention, I have signed my name hereto.

LEO J. GRUBMAN.
